VIOLIN PEG.

Inventor

John Lindstrom

By Watson E. Coleman
Attorney

UNITED STATES PATENT OFFICE.

JOHN LINDSTROM, OF HENDERSON, KENTUCKY.

VIOLIN PEG.

Application filed April 5, 1922. Serial No. 549,713.

To all whom it may concern:

Be it known that I, JOHN LINDSTROM, a citizen of the United States, residing at Henderson, in the county of Henderson and State of Kentucky, have invented certain new and useful Improvements in Violin Pegs, of which the following is a specification, reference being had to the accompanying drawings.

10 This invention relates to pegs more particularly designed for violins but adaptable to other stringed instruments, such as violin-cellos, guitars, banjos, and the like, and one of the objects of the invention is to provide a peg of this character which will positively hold against the rotative strain applied to it by the tension of the string.

Another object in this connection is to provide means whereby the frictional resistance 20 to the reverse rotation of the peg may be increased or decreased as desired. Still another object is to provide means whereby the string which, as usual, passes through a hole in the peg, may be positively engaged 25 so that short strings, incapable of being wrapped around the peg, may be utilized and positively engaged with the peg.

Other objects have to do with the details 30 of construction as will appear more fully hereinafter.

My invention is illustrated in the accompanying drawings, wherein:—

Figure 1 is a face view of a violin head showing my tightening peg in section;

35 Figure 2 is a section on the line 2—2 of Fig. 1;

Figure 3 is a like view to Figure 1, but showing a modification of the tightening peg;

40 Figure 4 is a fragmentary perspective view of the construction shown in Figure 3;

Figure 5 is a section on the line 5—5 of Figure 1;

Referring to Figure 1, 10 designates the 45 head of the violin of the usual character and slotted, as at 11. The body of the violin is not shown, as it forms no part of this invention. The peg in Figure 1 consists of a metallic pin 12 which at one end has a head 13 whereby the pin may be rotated.

The pin is hollow, as at 15, and has a diametrically extending opening 14 for the violin string. Entering one end of the peg 12 opposite the head 13 is a screw 16 having a head 17 nicked for the application of

a screw-driver or wrench. At the head end of the pin or peg 12 and between the violin head 10 and the head 13 are disposed a pair of washers 18 and 19, the washer 18 being slightly concavo-convex or dished and bearing against washer 19, which in turn bears against the edge face of head 10. The sleeve 20 is disposed over pin 12 and forms a bushing therefor and holds it in concentric relation to the hole through which it passes. 65

Between the opposite edge face of the violin head 10 and the screw head 17 is disposed a washer 21 bearing flat against the edge face of the head 10, and bearing on this washer is a coiled volute spring 70 22. A small washer 21^a bears against the small end of the spring 22 and the head 17 bears against this washer 21^a. Extending longitudinally through the head 13 and through this end of the hollow peg 12 is a 75 screw 23 having a head 23^a nicked for engagement by a screw-driver, the extremity of this screw 23 being reduced and intersecting the opening 14 so as to bind the string within this opening and act as 80 a set screw for this string. This permits a short string to be used which could not be wrapped around the pin.

In the use of this device, the screw 16 is initially tightened up as tight as possible 85 and then is turned back one-half a revolution in order to give the spring 22 a certain amount of play. Of course, where a short length string is to be used, it is passed through the opening 14, the screw 23 being 90 turned outward a few turns. Then the screw 23 is tightened up and the string will be held tightly. The washer 18 is annular in form for the passage of the peg and loosely surrounds the same and has a notch 95 18^a, while the peg has a lug which extends into this notch so that this washer 18 is held for rotation with the peg, as shown in Figure 5. The washer 19 bears against the edge face of the head 10 and does not rotate 100 with the peg.

With this construction, the spring 22 will cause such friction between the washers 18 and 19, between the washer 19 and the side edge of the head 10, and between the washer 105 21 and the side edge of the head 10 that the peg will be held in any adjusted position, while at the same time it is relatively easy to rotate the peg. This friction resisting any reverse movement of the peg may be in- 110

creased by setting up the screw 16 and, of course, it may be relieved by releasing the screw 16.

In Figures 3 and 4, I show a slightly modified form of the invention which, however, embodies the same principle as the device shown in Figure 1. In this figure, the numeral 10 designates the head of the violin, as before, and 11 the longitudinal slot in the head. Intersecting this slot is the hollow or tubular pin 25 formed with the opening 26 for the passage of the string. One end of the peg is formed with a worm gear wheel 27 which constitutes a head whereby the peg 15 may be turned and the peg is interiorly screw-threaded at this end for the passage of a screw 28 having a head 29. This screw 28 intersects the string passage 26 so that when this screw 28 is turned home it will bind the 20 string in the hole 26. Disposed against the edge face of the head 10 is a plate 30 which is approximately square in form and has a finger 31, this plate having outwardly projecting lugs forming bearings for the support of the usual threaded key 32 whereby the peg may be rotated. The opposite end of the peg 25 is interiorly screw-threaded for the reception of a screw 33, the head of this screw bearing against a washer 34, 30 which in turn bears against a volute spring 35, in turn bearing against a washer 37. In other words, the construction at this end of the peg is precisely similar to that illustrated in Figure 1. The finger or indicator 35 32, should the performer neglect to tighten the screw properly, will strike the neighboring peg 38 and plate 30 cannot, therefore, turn around. The plate 30 permits this device to be applied to a violin head without 40 the necessity of passing screws through the plate 30 into the violin head, inasmuch as the finger 31 bearing against the peg 38 will prevent any rotation of the plate 30. With this construction, the E string can be tightened 1/100 part of an inch or even less.

The device shown in Figure 3 is best adapted for children, as by this means very little strength is required to turn the peg.

I claim:

50 1. In a musical instrument, a tension head and a string peg therefor having a passage for a string, the string peg being hollow and interiorly screw-threaded, a head for the peg whereby the peg may be rotated having an opening aligning with the screw-threaded bore of the peg, and a screw extending through and engaging the screw-threads of the peg and intersecting said passage.

2. In a musical instrument, a tension head and a string peg therefor having a passage 60 for a string, the peg having a screw-threaded bore intersecting said passage and having a head at one end, whereby the peg may be rotated, and a screw extending longitudinally through the headed end of the pin and 65 engaging said bore and intersecting said passage.

3. A tension head for musical instruments having a longitudinally extending slot, a metal peg passing through the head and intersecting the slot, one end of the peg having a head, the opposite end being interiorly screw-threaded, a washer concentric to the peg and bearing against one face of the instrument head, a concavo-convex washer 75 loosely mounted on the peg to rotate therewith and concentric thereto and bearing at its edges against the first named washer, a screw engaging the interior screw-threads of the opposite end of the peg, a washer bearing against the side face of the instrument head adjacent said screw, and a coiled spring disposed between the screw head and said washer.

4. A tensioning head for musical instruments having a longitudinally extending slot, a metallic pin passing transversely through the head and intersecting the slot, the pin having a diametrically extending hole disposed within the slot, one end of the 90 pin having a head and the pin being interiorly screw-threaded, a screw engaging the interior screw-threads and having such a length that the extremity of the screw will intersect the string opening in the peg. 95

5. A tensioning head for musical instruments having a longitudinally extending slot, a peg passing transversely through the head and intersecting said slot, the peg having an opening for the passage of a 100 string and having at one end a head, the opposite end of the peg being interiorly screw-threaded, a concavo-convex washer mounted upon the peg at the headed end thereof for rotation with the peg, a second washer surrounding the peg and against which the first named washer bears, a bushing surrounding the peg, a screw engaging the interior screw-threads at the opposite end of the peg and having a head, a pair of washers 110 mounted upon the screw and one engaging the side face of the instrument board, and a volute spring disposed between the washers.

In testimony whereof I hereunto affix my signature.

JOHN LINDSTROM.
